UNITED STATES PATENT OFFICE.

HARRY K. HEDGES, OF LOS ANGELES, CALIFORNIA.

DESIGN FOR A MOTOR-CYCLE ATTACHMENT-BODY.

41,390.

Specification for Design.

Patented May 16, 1911.

Application filed August 22, 1910. Serial No. 578,487. Term of patent 14 years.

To all whom it may concern:

Be it known that I, HARRY K. HEDGES, a citizen of the United States, residing at Los Angeles, in the county of Los Angeles and State of California, have invented a new, original, and ornamental Design for Motor-Cycle Attachment-Bodies, of which the following is a specification, reference being had to the accompanying drawing.

The figure of the drawing is a perspective view of a motorcycle attachment body, showing my new and improved design, the said attachment comprising a covered body portion which has an open front completely

unobstructed from the top to the bottom thereof, the said body portion resting upon a flat frame including forwardly projecting and converging side pieces connected to each other and to the bottom of the body portion by ornamental diagonal braces.

I claim:—

The ornamental design for a motorcycle attachment body, as shown and described.

HARRY K. HEDGES.
